UNITED STATES PATENT OFFICE.

OSCAR RICHARD PETRELIUS, OF STOCKHOLM, SWEDEN, ASSIGNOR TO AKTIEBOLAGET HASSET, OF STOCKHOLM, SWEDEN.

METHOD FOR MANUFACTURING COLOR-PRINTS.

1,320,912.

Specification of Letters Patent.

Patented Nov. 4, 1919.

Application filed December 26, 1916. Serial No. 138,988.

To all whom it may concern:

Be it known that I, OSCAR RICHARD PETRELIUS, manufacturer, subject of the King of Sweden, residing at Riddargatan 17, 5 Stockholm, in the Kingdom of Sweden, have invented certain new and useful Improvements in Methods for Manufacturing Color-Prints, of which the following is a specification.

10 It has previously been proposed by the inventor to make color prints on paper, leather or the like by using a soft or elastic bed, a paper or the like and a relief block (electrotype or such like), by introducing a 15 moist print layer between the paper and one of the other two parts and by applying a great pressure to the paper or the like. Suitably the paint layer was applied to one of the paper surfaces, but it also could 20 be applied to the soft or elastic bed or to the relief block.

In an embodiment of the invention two papers or the like are used and the paint was introduced between the said papers; after 25 the pressure having been applied to the one paper both papers were separated.

The method is based upon the fact that on applying the pressure the paint will be attenuated in those places that come into 30 contact with the raised parts of the block or electrotype and pressed against the adjacent parts.

When printing according to the method as described above between endless surfaces, 35 for instance two rotating rollers, it has been found to be impossible to obtain a good print, mainly for the reason that the moist paint forms a smooth layer between the rollers, causing a sliding effect between the 40 paint layer and one of the rollers. This will cause a detrimental effect upon the print.

The present invention has for its object to eliminate this inconvenience while pressing between two endless surfaces (for instance two rollers) by joining or pressing together the two surfaces, between which the paint layer is located before the main or printing pressure by means of the block or electrotype is applied to the paper. Hereby the two parts, between which the paint layer is located, will be definitely jointed together and fixed in their relative position, so that on applying the pressure they will 50 not be displaced against each other. Another 55 advantage is that the moist paint is

not partially squeezed in one direction, when the paper is introduced between the two endless surfaces.

In case the print is made between a roller, serving as a relief block, and another soft 60 or elastic roller, the paint is preferably introduced between the paper or the like and the last named roller and thus the paper and this roller are joined before the printing pressure is applied to the paper.

On the annexed drawing one embodiment of a machine for performing the present method is shown schematically.

a is a rotating roller, suitably provided with an elastic surface, *b* a relief roller and *c* a paper unrolled from the roller *d*, on which paper a print, for instance a wall-paper print, is to be made. The moist paint can be applied to that surface of the paper *c* which is turned against the roller *a* by means 70 of the paint roller *e*, but the paint may also be applied to the roller *a* by means of a paint roller *f*. Of course other suitable devices could be used for applying the paint between *c* and *a*.

Suitably the paper is pressed against the roller *a* by means of rollers *g*, so that the paint is spread in the direction of the arrow *i*, whereby it is avoided that such a spreading is effected between the rollers *a* and *b*, 85 resulting in the smearing of the print. Hereby the result is obtained that the very high pressure between said two rollers *a* and *b* effects a uniform attenuation in all directions.

Besides this advantage another one is obtained, namely that no sliding or displacement effect can take place between the two parts between which the paint layer is located.

Instead of two rollers one roller and a counter-surface of any other shape could be used, having an even or curved surface and being movable up and down or having a reciprocating motion. It is, however, also possible to use instead of one or both rollers, 100 endless bands or the like of leather, caoutchouc, steel or the like.

h is a pressing strip, projecting into the space between the two rollers and pressing 105 the paper *c* against the roller *a* just before it is introduced and pressed between the two rollers *a* and *b*.

Claims.

1. A process for making prints consisting 110

2
of applying paint to a sheet of material, placing said sheet in contact with a roller with the painted side thereagainst; applying preliminary pressure progressively over 5 said sheet to consolidate the paint, and finally pressing a printing element against said paper.

2. A process for making prints consisting in applying paint to a sheet of material, 10 placing said sheet in contact with a roller having an elastic surface with the painted side thereagainst; applying preliminary pressure progressively over said sheet to consolidate the paint, and finally pressing 15 a printing roller against said paper.

3. A process for making prints consisting in applying paint to a sheet of material, placing said sheet in contact with a roller with the painted side thereagainst; applying preliminary pressure progressively over 20 said sheet to consolidate the paint, and finally pressing a printing element against the unpainted side of said sheet.

In testimony whereof I affix my signature in presence of two witnesses.

OSCAR RICHARD PETRELIUS.
